(57) **CLAIM**

The ornamental design for a wall block body, as shown and described.

DESCRIPTION

FIG. 1 is a front bottom perspective view of a first embodiment of a wall block body according to my new design.

FIG. 2 is a back bottom perspective view of the wall block body of FIG. 1.

FIG. 3 is a bottom plan view of the wall block body of FIG. 1.

FIG. 4 is a top plan view of the wall block body of FIG. 1.

FIG. 5 is a front plan view of the wall block body of FIG. 1.

FIG. 6 is a back plan view of the wall block body of FIG. 1.

FIG. 7 is a left side plan view of the wall block body of FIG. 1.

FIG. 8 is a right side plan view of the wall block body of FIG. 1.

FIG. 9 is a front bottom perspective view of a second embodiment of a wall block body according to my new design.

FIG. 10 is a back bottom perspective view of the wall block body of FIG. 9.

FIG. 11 is a bottom plan view of the wall block body of FIG. 9.

FIG. 12 is a top plan view of the wall block body of FIG. 9.

FIG. 13 is a front plan view of the wall block body of FIG. 9.
FIG. 14 is a back plan view of the wall block body of FIG. 9.
FIG. 15 is a left side plan view of the wall block body of FIG. 9.

FIG. 16 is a right side plan view of the wall block body of FIG. 9.

FIG. 17 is a front bottom perspective view of a third embodiment of a wall block body according to my new design.

FIG. 18 is a back bottom perspective view of the wall block body of FIG. 17.

FIG. 19 is a bottom plan view of the wall block body of FIG. 17.

FIG. 20 is a top plan view of the wall block body of FIG. 17.
FIG. 21 is a front plan view of the wall block body of FIG. 17.

FIG. 22 is a back plan view of the wall block body of FIG. 17.

FIG. 23 is a left side plan view of the wall block body of FIG. 17.

FIG. 24 is a right side plan view of the wall block body of FIG. 17.

FIG. 25 is a front bottom perspective view of a fourth embodiment of a wall block body according to my new design.

FIG. 26 is a back bottom perspective view of the wall block body of FIG. 25.

FIG. 27 is a bottom plan view of the wall block body of FIG. 25.

FIG. 28 is a top plan view of the wall block body of FIG. 25.

FIG. 29 is a front plan view of the wall block body of FIG. 25.

FIG. 30 is a back plan view of the wall block body of FIG. 25.

FIG. 31 is a left side plan view of the wall block body of FIG. 25; and,

FIG. 32 is a right side plan view of the wall block body of FIG. 25.

The broken lines shown in the drawings are for illustrative purposes only and form no part of the claimed design.
